US00D804466S

(12) **United States Design Patent** (10) Patent No.: **US D804,466 S**
(45) Date of Patent: ** Dec. 5, 2017

(54) **ELECTRONIC DEVICE**

(71) Applicant: **Intel Corporation**, Santa Clara, CA (US)

(72) Inventors: **James Okuley**, Portland, OR (US); **Markus Wierzoch**, Seattle, WA (US); **Tim B. Hulford**, Portland, OR (US); **Ben Collette**, Seattle, WA (US)

(73) Assignee: **Intel Corporation**, Santa Clara, CA (US)

(**) Term: **15 Years**

(21) Appl. No.: **29/554,617**

(22) Filed: **Feb. 12, 2016**

Related U.S. Application Data

(62) Division of application No. 29/473,872, filed on Nov. 26, 2013, now Pat. No. Des. 749,561.

(57) **CLAIM**

The ornamental design for an electronic device, as shown and described.

DESCRIPTION

FIG. 1 is a perspective view of an electronic device showing our new design;

FIG. 2 is a front view thereof;

FIG. 3 is a back view thereof;

FIG. 4 is a side view thereof;

FIG. 5 is an opposite side view thereof;

FIG. 6 is a top view thereof; and,

FIG. 7 is a bottom view thereof.

The broken lines shown in the figures depict environment or structure only and form no part of the claimed design.

1 Claim, 7 Drawing Sheets
